UNITED STATES PATENT OFFICE

RAYMOND D. FOLTZ, OF SOUTH ORANGE, NEW JERSEY, ASSIGNOR TO M. H. DETRICK COMPANY, OF CHICAGO, ILLINOIS, A CORPORATION OF ILLINOIS

FURNACE CONSTRUCTION

Application filed November 30, 1928. Serial No. 322,659.

This invention relates to furnace construction, and pertains particularly to wall construction for furnaces which are operated at high temperatures.

5 One of the objects of the invention is the provision of an improved refractory wall structure particularly adapted for use as the main or closure wall of the furnace chamber in conjunction with the so-called water walls 10 or tube walls of a boiler furnace or the like.

Another object of the invention is the provision of an improved furnace wall employing refractories and tubes in combination.

Yet another object is the provision of an 15 improved refractory wall, for furnace chambers and the like, in which the refractories are definitely retained in the desired wall plane, yet may be removed and replaced with facility from the outside of the furnace for 20 the making of repairs in either limited or extended areas of the wall.

Another object of the invention is the provision of a wall structure having characteristics and advantages above mentioned and 25 which may be built or assembled expeditiously. Other and further objects of the invention will be pointed out or indicated herein-after or will become apparent to one skilled in the art upon an understanding of it or its 30 employment in practice.

In the accompanying drawings forming a part of this specification I illustrate certain wall constructions embodying the invention, but it is to be understood that these and the 35 following description of the same are presented by way of example and illustration merely, and that these examples are not to be regarded as exhausting the variations of construction in which the invention may be embodied 40 or as imposing on the appended claims any limitations short of the true and most comprehensive scope of the invention in the art.

In the drawings

Fig. 1 represents a horizontal section of a 45 portion of a wall embodying the invention in one form;

Fig. 2 is a detail of the same on a larger scale;

Fig. 3 is a detail in the nature of a part 50 sectional elevation of a wall portion;

Fig. 4 is a perspective view of a brick support;

Fig. 5 is a perspective view of a retaining or anchoring member;

Fig. 6 shows a part outside elevation, with 55 portions of the structure removed, and

Fig. 7 is a detail similar to Fig. 3 but showing a modified construction.

In certain kinds of boiler furnaces which are intended to burn fuel rapidly and develop continuously a large quantity of heat for application to the boilers, it is sometimes desired to use water wall or tube wall features, which are in the nature of water tubes 60 extending along portions of the inner wall surfaces and connected at their ends to headers which are in turn connected with the boiler or other circulation system. These tubes are supplied with water and in effect constitute part of the boiler as well as the wall 65 and function as heat-transferring elements whereby heat from the furnace chamber is transmitted to the water which they contain. In conjunction with them it is necessary to employ some kind of an external closure 70 wall to form a tight closure for the furnace chamber in which the combustion gases and the tube wall are enclosed, and the so-called tube wall may cover more or less of the interior surface area of this closure wall. 75 Sometimes slabs or blocks of refractory material are attached to or supported laterally by the wall tubes to form a heat-conducting sheathing for them on the side toward the combustion chamber. 80

The construction of the outer wall, which hereinbefore and hereinafter is termed a closure wall, has presented certain difficulties because of its proximity to the wall tubes, and various difficulties in the operation and 85 maintenance of such furnaces have developed from the tendency of closure walls as heretofore constructed to bulge into the furnace chamber and to impose inward pressure or weight upon the wall tubes, such pressures 90 resulting either from the nature of the closure wall construction as originally installed, or from deformation of the closure wall by heat.

The present invention finds particular 100

utility in furnace wall constructions wherein such wall tubes are employed, although its advantages are not limited to such constructions alone. It provides a structure 5 wherein the wall tubes are relieved and safe-guarded from pressures from the closure wall, which latter at the same time affords a factor for influencing the heat transfer functions of the wall tubes. Furthermore, 10 it affords a construction wherein the closure wall refractories and the wall tubes afford each other mutual protection in an improved and advantageous manner. Moreover, it 15 simplifies the erection of such wall constructions and permits the repair of the closure wall entirely from the outside of the furnace without interference from the wall tubes, and even without necessitating shutting down of the furnace.

20 The nature of the invention will be most quickly ascertained by a consideration of the illustrative constructions shown in the drawings. In the arrangements here shown, the reference numeral 10 designates columns, in 25 the nature of steel I-beams, which are ranged along the course of the wall, being suitably supported, as on appropriate foundations at the lower ends, and connected at proper vertical intervals by transverse members which 30 maintain them in the desired spacing and parallel relationship. Steel channel members 11 are secured to the inner flanges of these I-beams and constitute in fact a part of the vertical columns, as they extend vertically with the I-beams. Flanges 11^a of 35 these channel members are presented outwardly with respect to the furnace chamber. These columns are supported in the desired upright position in any appropriate fashion.

40 The construction illustrated in Figs. 1, 2, 3 and 6 includes a number of brick supports 12 made of a metal which can stand considerable heating without loss of its tensile strength, such as cast iron. These are of 45 angular form and provided along the inner face of one flange with a longitudinal rib 12^a and on the back of said flange with the thickened portions or spacing lugs 12^b at the ends. Bolt holes 12^c pass through said flange at 50 said thickened portions. These brick supports are secured end to end in horizontal position to the columns 10 by means of bolts 14, so that they afford horizontally arranged shelves presented toward the furnace chamber. The wall tubes are designated 15 and are spaced from the brick supports a suitable distance to accommodate a closure wall of the desired thickness. These wall tubes are connected at their upper and 55 lower ends to headers arranged in any of the customary fashions. The closure wall includes the wall refractories 16, 17 and 18. The refractories 16 and 17 are provided with T-shaped slots at one end, the refractories 60 16 being of uniform thickness, and the re-

fractories 17 having the portion at the un-slotted end somewhat thickened to provide a projecting or offset portion 17^a. Refractories 16 and 17 are preferably of the same length and width. The refractories 18 preferably are of substantially the same length and width as the refractories 16, but they are thicker at one end than at the other so as to provide the offset portion 18^a for a part 70 of their length corresponding to the distance between the slotted end and the offset shoulder of the refractories 17^a. A wall of sectional construction is built up of these refractories, the respective sections being disposed one above another and being independently supported on the brick supports 12. In each section the lowest course is formed of the refractories 17, which are disposed with their slotted ends resting on the brick 75 supports and their offset portions 17^a depending across the inner margins of the horizontal flanges of said brick supports. On the lowermost course of the refractories 17 in each section are placed superimposed courses of refractories 16. Preliminary to 80 the placing of the refractories as above described, tile-retaining or anchoring members of form such as illustrated in Fig. 5 are placed on the brick supports. These anchoring members are designated generally by the reference numeral 19, and are iron castings, each formed with a web portion 19^a having lateral flanges 19^b along one margin and a connecting member 19^c projecting from the opposite margin. The web portion also has 85 a shouldered projection 19^d beneath the connecting member 19^c. The flanges 19^b and the web 19^a are of such size and form as to be accommodated loosely within the slots of the refractories 16 and 17. These anchoring members are disposed in collateral association 90 on the brick supports, the connecting members 19^c being engaged over the upper margin of the upright flange of the brick supports and the projection 19^d being engaged below the rib 12^a of the latter, the anchoring members thus being maintained 95 in vertical position with their lower ends resting on the shelf portion of the brick supports. As the successive courses of refractories 17 and 16 are laid, their T-shaped 100 slots are threaded onto these anchoring members, and thus they are held against horizontal displacement either inwardly or outwardly with respect to the brick supports and the wall tubes. The topmost course of each section is formed of refractories 18 which 105 rest on the subjacent course of refractories 16. The refractories 18 are disposed so that their offset portions 18^a overlap vertically the offset portions 17^a of the lowermost course 110 of refractories in the superjacent section, but with space between the top faces of the refractories 18 and the lower faces of said refractories 17 and the superjacent brick sup-

port. This space is filled with a compressible refractory material 20, such as a mixture of fire clay and asbestos, to close the joint between the sections. The vertical faces of the 5 projecting portions 17^a and 18^a are in abutment, so that they also close the joint, while at the same time allowing upward movement of the refractories 18, incident to thermal expansion without subjecting the refractories 10 or the brick supports 12 to a resulting pressure. The refractories in the respective courses are placed in lateral abutment, so that a continuous refractory closure is formed, excepting where desired openings 15 may be provided. The anchoring members 19 may be susceptible of sliding movement longitudinally of the wall, but are maintained in their desired vertical position and are held against shifting inwardly or outwardly. 20 The refractories may take any of various forms, certain variations being shown in the drawings by way of example. If it is desired to partly cover or shield a portion of the area of the wall tubes, the refractories may 25 be of such length as to extend between the tubes, their inner corner portions being concave so as to conform to the contour of the tubes and permit the latter to occupy a portion partly in-set into the refractory wall, as 30 illustrated in Figs. 2 and 3 and in the upper portion of Fig. 1. Or the refractories may be of such length as to terminate in a plane adjacent the tubes, as illustrated in the portion of Fig. 1 bracketed at N. Or where the 35 center spacing of the tubes exceeds the width of the refractories, refractories having one corner portion concave may be used, as illustrated in the lower portion of Fig. 1. The spacing of the tubes and the extent to which 40 it may be desirable to in-set them into the refractory wall will depend on the amount of heat transference desired from the furnace chamber into the water in the tubes and the temperature which it is desired to maintain in 45 the furnace chamber. It is desirable, however, that the width of the refractories correspond to the spacing of the tubes so that the vertical joints of the wall will be behind the tubes, and thus shielded thereby. 50 It will be appreciated that the tubes exercise a cooling and shielding, and hence temperature-limiting, effect on the adjacent refractories. Hence the refractory wall may be heat insulated externally, and this may be 55 done by covering them externally with lagging material 21. An appropriate external sheathing may be formed of plates 22 which are flanged at their margins and have the lateral flanges bolted to the flanges 11^a, and 60 the horizontal flanges bolted to the meeting flanges of superjacent and subjacent plate sections. In Fig. 6 is shown a part wall elevation with one of the plate sections removed. As there illustrated, it is desirable that the 65 horizontal joints of the sheathing sections coincide approximately with horizontal joints of the sectional wall. By removal of a sheathing plate and the lagging material which it covers, access may be had to any wall section from the outside of the furnace, for 70 replacement of wall refractories or access to the tubes. Refractories are easily removed and replaced in any section by removing so many as may be necessary of the uppermost course of refractories 18 directly outwardly. 75 This permits the subjacent refractories to be lifted from the anchoring members 19 and removed outwardly, and the refractories may be replaced in the wall structure as readily, such removals and replacement being made 80 in the selected section without involving removal of refractories from any other section. It will be observed that by virtue of the construction described, the wall refractories are definitely anchored against inward displacement such as would subject the tubes to thrusts, the refractories being so maintained by virtue of the independent support of the wall sections, the anchorage of the refractories 16 and 17 by the members 19 and of the 85 refractories 18 by their abutment with the refractories 17. Additional anchorage of refractories 18 may be provided by anchoring irons 24 as described in my U. S. Letters Patent No. 1,747,824 for furnace wall construction, certain of the refractories 18 in each course being free of such anchoring irons; however, to permit their withdrawal directly outwardly. Not only are the wall 90 refractories thus easily replaceable, but likewise the anchoring members 19 and brick supports 12, any of which may be removed and replaced entirely by operations from the 95 outside of the furnace. 100

In Fig. 7 is illustrated a modified construction wherein bar members 12' are bolted to the flanges of the members 10 and the webs of the channels 11^a and may extend continuously across a number of the columns. The anchoring members 19' are cast iron members like those previously described, with the exception that each is additionally formed with a bottom shelf portion 12^x which extends to a distance beyond the margins and inner face of the flanges 19^b and constitutes 105 a brick support. These anchoring members are connected to the supporting members 12' by means of the parts 19^c and 19^d as above described, so that they are supported in an upright position with the shelf portions 12^x 110 in a generally horizontal position. Wall sections are then built up as above described, the refractories of the lowermost course of each section being supported on the shelf portions 12^x. 115

It will be observed that by virtue of the constructions above described, a continuous refractory wall may be provided in association with wall tubes, the refractories and the tubes being maintained in an association 120 125 130

wherein the refractories exercise the desired heat radiating effect on the tubes and the tubes a desired cooling or temperature-limiting effect on the refractories, the tubes at the same time being definitely safeguarded against thrusts from the refractories and the portions of the wall structure as a whole being maintained in the proper association. No necessity is imposed on the tubes for the support of any part of the wall, either in its assembled condition or incident to its assembly, and the wall may be assembled and repaired entirely without the use of forms and without interference with or from the tubes.

15 What I claim is:

1. In a furnace having a plurality of water tubes arranged collaterally in a row, a wall construction comprising a supporting frame spaced from the row of tubes, brick supports carried by said frame, refractories arranged to form wall sections supported independently one above another by said brick supports to constitute a closure wall extending along the row of tubes, and anchoring means extending parallel with the tubes and anchoring refractories in the wall to maintain their inner ends in the desired association with the tubes.

2. In a furnace having a row of water tubes arranged for exposure within the furnace chamber, a wall construction comprising a frame spaced from the row of tubes, brick supports carried by the frame, refractories supported by said brick supports to form a closure wall between the tubes and frame and spaced from the latter, heat-insulating material applied to the outer surfaces of the refractories, and vertically extending anchoring members anchored to the frame and each engaging a series of refractories to hold them against shifting toward or from the tubes but permitting them upward shifting movement in the wall.

3. In a furnace having a row of water tubes arranged for exposure within the furnace chamber, a wall construction comprising a frame disposed collaterally of and spaced from the row of tubes, brick supports carried by the frame, refractories arranged on the brick supports to form wall sections independently supported one above another between the tubes and the frame, heat-insulating material applied to the outer surfaces of the refractories, and tile-retaining members anchoring the refractories against displacement toward the tubes.

4. In a furnace, a wall construction comprising, in combination, a frame, wall sections supported by the frame independently one above another, said wall sections formed of superimposed courses of refractories, anchoring members connected with the frame and engaging refractories in the wall to hold them against displacement inwardly, said anchoring members being spaced apart to

permit withdrawal of refractories outwardly of the wall from the various sections.

5. In a furnace, a wall construction comprising, in combination, a frame, brick supports carried thereby one above another, tile-retaining members connected with the brick supports and extending upwardly therefrom and terminating at a distance from the superjacent brick supports, refractories carried on the brick supports to form wall sections independently supported one above another, the top refractories of respective sections overlapping refractories in superjacent sections, said tile-retaining members engaging refractories in respective sections to hold them against displacement inwardly from the wall, all the refractories of a section being removable outwardly from the wall through the space between tile-retaining members and superjacent brick supports.

6. In a furnace, a wall construction comprising, in combination, a wall supporting frame including spaced metallic column members, a wall sheathing comprising separately removable plates secured to the frame, wall sections independently supported on the frame one above another to form a continuous wall, said sections comprising superimposed refractories having slotted outer ends, tile-retaining members of heat resistant metal attached to the frame and engaging the slotted ends of refractories in respective sections to hold them spaced from the column members and anchor them against inward displacement, lagging material covering the outer surfaces of the refractories to insulate the column members and plates from them, the upper course of refractories in each section being removable outwardly from the wall independently of the superjacent section, and the other refractories of the sections being removable upwardly on their retaining members and outwardly from the wall.

7. A wall constructed as specified in claim 1 and wherein the refractories of a section are removable outwardly from the wall independently of other sections.

8. A furnace wall structure comprising a frame including spaced metallic column members constituting the principal load-carrying elements of the structure, brick supports carried by the frame in vertically spaced relationship at one side thereof, refractories arranged to form wall sections carried by the brick supports and associated to form a furnace chamber wall spaced laterally from the columns, heat-insulating material covering the outer surfaces of the refractories and extending between them and the columns, and anchoring members anchored to the frame and holding the refractories against displacement inwardly from the wall.

9. A furnace wall structure as specified in claim 8 and wherein the anchoring mem-

bers extend vertically and have anchoring engagement each with a plurality of refractories, said anchoring members being spaced from superjacent brick supports to permit withdrawal of all of the refractories outwardly from respective wall sections after removal of the insulating material.

5 In testimony whereof I have hereunto subscribed my name.
